(57) **CLAIM**

The ornamental design for a multifunctional car air vent mount phone ring, as shown and described.

DESCRIPTION

FIG. 1 is a perspective view generally taken from one side of a multifunctional car air vent mount phone ring showing the design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof; and,

FIG. 9 is a perspective view showing the multifunctional car air vent mount phone ring of FIG. 1 in an open position.

1 Claim, 7 Drawing Sheets
